WRIST WATCH STAND

Saul Ritter, New York, N. Y.

Application June 12, 1953, Serial No. 25,467

Term of patent 3½ years

(Cl. D80—9)

Fig.1.

Fig.2.

Fig.3.

Fig. 1 is a front elevational view of a wrist watch stand showing my new design;

Fig. 2 is a rear elevational view of the wrist watch stand shown in Fig. 1, and

Fig. 3 is a transverse sectional view taken through the center of the wrist watch stand.

I claim:

The ornamental design for a wrist watch stand, as shown.
